UNITED STATES PATENT OFFICE.

FREDERICK R. SEIDENSTICKER, OF WEST MERIDEN, CONNECTICUT,
ASSIGNOR TO BRADLEY & HUBBARD, OF SAME PLACE.

DESIGN FOR LAMP-BRACKETS.

Specification forming part of Design No. 7,538, dated July 14, 1874; application filed June 3, 1874.
[Term of Patent 7 years.]

CASE B.

To all whom it may concern:

Be it known that I, FREDERICK R. SEIDENSTICKER, of West Meriden, in the county of New Haven and State of Connecticut, have invented a new Design for Lamp-Bracket; and I do hereby declare the following, when taken in connection with the accompanying illustration and the letters of reference marked thereon, to be a full, clear, and exact description of the same, and which said illustration constitutes part of this specification, and represents a perspective view.

This invention relates to a design for bracket for supporting a lamp or other burner; and consists in the peculiar configuration of the arm, together or separately, as more fully hereinafter described.

The bracket-arm A, from its point of connection with the base to the lamp, is substantially crescent-shaped, the inner or upper curve of less

diameter than the lower, making the arm to taper from the base forward. Midway of the arm is the representation of a cock, B, in "key-stone form," a scroll-work below representing the handle of the plug. The upper or base end of the arm rises into a scroll from above the point of connection with a bat's-wing shaped brace, C, running down to the base, all as shown and described.

I claim as my invention—

The design for lamp-bracket consisting of the crescent-shaped arm A, terminating in the bat's-wing brace C, and scroll shape at the base end, and with the representation B of a cock, as shown and described.

FREDERICK R. SEIDENSTICKER.
